UNITED STATES PATENT OFFICE.

HARRY THAYER KINGSBURY, OF KEENE, NEW HAMPSHIRE.

DESIGN FOR A TOY-CAR ROOF.

SPECIFICATION forming part of Design No. 31,420, dated August 15, 1899.

Application filed July 13, 1899. Serial No. 723,742. Term of patent 14 years.

To all whom it may concern:

Be it known that I, HARRY THAYER KINGSBURY, a citizen of the United States, residing at Keene, in the county of Cheshire, State of New Hampshire, have invented a certain new and original Design for a Toy-Car Roof, of which the following is a description, reference being had to the accompanying drawing and to the letters and figures of reference marked thereon.

My invention relates to a new and original design for toy-car roofs; and the leading feature consists in the peculiar shape and configuration of the car-roof, as hereinafter described.

The design is illustrated in the accompanying drawing, in which the figure represents a perspective view of a car-roof embodying my design.

The leading feature of the design consists in the roof portion, which is formed with a raised central portion B, having the downwardly-bent end portions 5, connected with the roof proper of the car by the portions having the openings 4, the roof portion of the car on either side of the raised portion being indicated at 6.

Having thus described my invention, what I claim, and desire to secure by Letters Patent, is—

The design for the roof of a toy car, substantially as shown and described.

In testimony whereof I affix my signature in presence of two witnesses.

HARRY THAYER KINGSBURY.

Witnesses:

W. L. MASON,
C. L. STURTEVANT.
